CHARLES MARCUS, OF NEW YORK, N. Y., ASSIGNOR TO ECLIPSE MACHINE COMPANY,
OF ELMIRA HEIGHTS, NEW YORK, A CORPORATION OF NEW YORK

IGNITION SYSTEM

Application filed November 12, 1927. Serial No. 232,927.

This invention relates to an ignition system, and more particularly to a starting ignition system for internal combustion engines.

When magnetos are employed to produce ignition current for internal combustion engines, current supplied thereby is frequently ineffective to properly start the engine, due to the low speed of rotation of the crank shaft and consequently of the magneto armature during the starting operation. Accordingly, it has heretofore been proposed to provide means, in combination with a storage battery, for supplying starting current to an internal combustion engine, switch means being employed, after the engine is started, to disconnect the battery and to thereafter employ the magneto as a source of ignition current.

It is an object of this invention to provide novel means for supplying ignition current to an internal combustion engine during the starting operation.

Another object of this invention is to provide means of the above character which is particularly adapted for supplying starting ignition current to an aeroplane motor.

Another object is to provide novel means, in combination with starting mechanism, for supplying ignition current during the starting operation of an internal combustion engine, said means thereafter being adapted to be disconnected.

Another object is to provide novel means, directly associated with starting mechanism and a battery, for supplying starting current to an internal combustion engine, said means being particularly adapted for use in combination with starters of the inertia type extensively employed for starting aeroplane engines.

In the accompanying drawings is illustrated one embodiment of the present invention, the starting mechanism and a portion of the current supply means being shown in perspective, other portions of the current

supply means being diagrammatically shown. It is to be expressly understood, however, that these drawings are for purposes of illustration only and are not designed as a definition of the limits of the invention, reference being had for this purpose to the appended claims.

In the form shown, the present invention comprises, in combination with an engine starter of the inertia type, a source of current, such as a battery 1, adapted to supply the necessary ignition current for starting the engine, a portion of the latter being shown in perspective at 2. In the illustrated embodiment, the starter mechanism comprises a hand crank 3 adapted to be operatively connected to a shaft 4 carrying a worm 5 adapted to mesh with a worm gear 6 which is operatively connected to suitable motion transmitting means for rotating the inertia element (not shown). Since devices of this character are well known in the art, a detailed description of the same is unnecessary here, it being pointed out merely that while the shaft 4 is illustrated of the manually operable type, it is to be understood that this shaft may be driven by other suitable means, such as an electric motor.

Means are provided for delivering current from the battery to the engine spark plugs (not shown), said means being combined with the starter mechanism. Rigidly secured to shaft 4, adjacent one end thereof, is a gear 7 which meshes with a pinion 8 carried on the end of a shaft 9, the latter being rotatably mounted in bearings positioned in a housing 10 secured to, or formed integrally with, the starter housing 11. If desired, housing 10, 11 may comprise a portion adapted to enclose gears 7 and 8.

A cam member 12 is fixedly attached to shaft 9 for rotation therewith. The member 12, which may be provided with any suitable number of projecting portions, is adapted to engage a contact arm 13 and

swing the same about a pivot member 14 suitably provided on the housing 10, 11, against the tension of a spring 15 which is secured, at one end, to said arm and at its opposite end is fixedly attached to a projecting member 16 that may be mounted on the housing 10. Adapted to coact with contact arm 13 is a stationary contact member 17 to which is operatively connected the primary 18 of an induction coil, said primary being connected through a suitable switch 19 to the battery 1. In inductive relation with coil 18 is a secondary coil 20 which is connected to the battery intermediate primary coil 18 and switch 19, as at 21, the opposite end of said secondary coil being operatively connected to the distributor (not shown) for controlling the flow of ignition current to the spark plugs in the engine cylinders. The battery, primary coil 18 and contacts 13, 17 are preferably grounded as indicated at 22 and 23. If desired, a condenser 24 may be shunted across the contacts 13 and 17 to prevent sparking.

When it is desired to start the engine the operator actuates crank 3 and shaft 4, whereby energy is stored in the inertia element of the starter. When the stored energy is utilized by throwing the starter into mesh with the crank shaft of the engine, switch 19 is closed to complete the circuit through battery 1, contacts 13, 17 and primary coil 18. Rotation of shaft 4 is transmitted through gearing 7, 8 and shaft 9 to cam 12, whereupon contacts 13, 17 are opened and closed to interrupt the flow of current from battery 1. This interrupting of the current delivered by battery 1 induces a high potential current in the secondary coil 20 and the current thus induced is led to the distributor and from thence to the various spark plugs, whereby ignition current is provided for starting the engine. Due to the gearing employed, cam 12 rotates at high speed so that a number of current impulses are induced in the secondary coil 20 during the time that the distributor arm passes each contact connected to the various spark plugs of the engine. Since the distributor arm is drivably connected to the engine crank shaft, proper timing of the ignition current in the cylinders is effected. After the engine is started, switch 19 is opened and the ignition current is then supplied direct from the magneto, or other suitable current generating means usually employed.

It is customary to provide a suitable battery in aeroplanes in order to supply current for navigational lights, land lights, radio apparatus, etc., and by the use of the present invention this same battery may be utilized to provide starting current for the engine. The necessity for special ignition apparatus for starting, which adds to the dead weight

that must be carried by the plane, is thus largely eliminated.

The rotation of shaft 4 is relatively slow and gears 7 and 8 are preferably so selected that shaft 9 will rotate at a relatively high speed. Cam 12 is provided with a suitable number of projections to insure that a selected number of sparks will be provided to the spark plugs, via the distributor, for each compression stroke of the pistons.

Since the starter mechanism is in use only at the time of starting the engine, excessive wear is not thrown on gears 7, 8 and contacts 13, 17. The apparatus is extremely compact and avoids the necessity for employing an additional magneto for starting purposes. The driving mechanism for cam 12 may vary within wide limits, and the invention is not limited to the use of any particular type of inertia starter. Practically no weight is added which is of primary consideration in aeroplane construction. The device may be readily installed and is certain in operation. Various changes may be made in the details of construction without departing from the invention defined in the following claims.

What is claimed is:—

1. In combination with an engine starter, a battery, means including a cam mounted on and actuated by said starter, contacts controlled by said cam, an induction coil having the primary thereof in circuit with said contacts, and a switch for placing said battery in circuit with said primary and contacts.

2. In combination with starting mechanism for an internal combustion engine, a shaft rotatably mounted on and adapted to be driven by said starting mechanism, a cam carried by said shaft, a source of current supply, a circuit therefor, means actuated by said cam for making and breaking said circuit, and means for conducting the current to the engine for starting purposes.

3. In combination with a starter for an internal combustion engine, a battery, a member rotatably mounted on said starter, means secured to said member and adapted to be driven by said starter, contacts adapted to be opened by said member, yielding means carried by the starter for closing said contacts, an induction coil having its primary in circuit with said contacts, and switch means for placing said battery in circuit with said primary.

4. In combination with an internal combustion engine, starting mechanism therefor, and means for supplying ignition current to the engine during the operation of said starting mechanism, said means comprising a cam mounted on and adapted to be driven by said starting mechanism, a battery, and means controlled by said cam for delivering high tension current from the battery to the engine.

5. In combination with a starter, of the inertia type, for internal combustion engines, a shaft for storing energy in the inertia element of said starter, means including a cam
5 adapted to be driven by said shaft, a pair of contacts adapted to be opened by said cam, yielding means for normally maintaining said contacts in engagement, and current supply means controlled by said contacts for
10 supplying starting current to the engine.

10 In testimony whereof I have signed this specification.

CHARLES MARCUS.
